UNITED STATES PATENT OFFICE.

HENRY M. CROWTHER, OF KINGMAN, ARIZONA.

VALVE-GRINDER.

1,314,949.

Specification of Letters Patent. Patented Sept. 2, 1919.

Application filed February 8, 1919. Serial No. 275,895.

To all whom it may concern:

Be it known that I, HENRY M. CROWTHER, a citizen of the United States, residing at Kingman, in the county of Mohave and State 5 of Arizona, have invented new and useful Improvements in Valve-Grinders, of which the following is a specification.

This invention relates to automatic valve grinders and consists of the novel features 10 herein shown, described and claimed.

My object is to provide simple means whereby the inlet and exhaust valves of an 15 internal combustion engine may be automatically rotated step by step by the reciprocation of the valve stems, and to provide means whereby the grinding action may be discontinued at will.

A further and more specific object of my 20 invention is to mount an automatic valve grinder upon an internal combustion engine so as to rotate the inlet and exhaust valves step by step by the reciprocation of the valve stems and to make the step by step motion irregular.

Another object of my invention is to make 25 an automatic valve grinder which will slightly rotate the valves both on the seat and off the seat so that the grinding action may be continued indefinitely without overgrinding.

Figure 1 is a fragmentary sectional elevation showing an automatic valve grinder embodying the principles of my invention in position for use.

Fig. 2 is a fragmentary sectional detail at 30 right angles to Fig. 1 and taken on the line 2-2 of Fig. 1.

Fig. 3 is a horizontal sectional detail on the line 3-3 of Fig. 1 and looking downwardly.

Inlet and exhaust valves 1 and 2 have stems 3 and 4 extending downwardly through a casing 5 and operated by cams 6 and 7 upon a cam shaft 8. A rectangular opening 9 is formed through the stem 3 and a double headed key 10 is inserted through this opening and the central portion of the key is reduced so that when the key settles down the heads are upon opposite sides of 45 the stem so as to hold the key in place. A

hub 11 fits loosely upon the stem 3 and has a recess in its lower end to receive the heads of the key 10 so that when the hub settles down upon the key the hub is held from rotating on the stem. A spring seat 12 extends 55 outwardly from the lower end of the hub 11. A ball bearing 13 is mounted in the spring seat 12 and a spring 14 is placed upon the stem 3 with its upper end bearing against a spring seat 15 upon the casing 5 60 and its lower end resting upon the ball bearing 13 in the spring seat 12; the tension of the spring 14 being exerted to hold the valve 1 closed. The cam 6 serves to open the valve 1.

An annular rim 16 extends upwardly from the outer edge of the spring seat 12 concentric to the hub 11, and ratchet teeth 17 are formed in the upper edge of this rim.

In a like manner a key 18 is mounted through an opening 19 in the stem 4, a hub 20 fits upon the heads of the key 18 and carries a spring seat and ball bearing to support a spring 21 and an annular rim 22 75 having ratchet teeth 23. The spring 21 engages a spring seat 24 upon the casing 5 and the tension of the spring serves to hold the valve 2 upon its seat.

A bearing plate 25 fits against a vertical wall 26 of the water jacket and is held in place by cap screws 27. The bearing plate 25 is located in a plane half way between the springs 14 and 21 and somewhat above the lower ends of the springs. A horizontal bearing 28 extends outwardly from the bearing plate 25. A shaft 29 is rotatably mounted in the bearing 28 and the ends of the shaft are turned down to form eccentric pawl pivots 30. Pawls 31 and 32 are loosely mounted upon the eccentric pawl pivots 30, the free ends of the pawls 31 and 32 being in position to engage the ratchet teeth 17 and 23. Leaf springs 33 and 34 are rigidly secured to the bearing 28 by screws 35 and the free ends of the springs engage the pawls 31 and 32 to press the pawls downwardly into engagement with the ratchet teeth 17 and 23. Secondary ratchet wheels 35 and 36 are fixed upon the eccentric pawl 100

pivots 30 outside of the heads of the pawls 31 and 32. Secondary pawls 37 and 38 are pivotally mounted upon the pawls 31 and 32 to engage the secondary pawl wheels 35 and 36, and secondary springs 39 and 40 are fixed to the pawls 31 and 32 to engage the secondary pawls 37 and 38 to hold the secondary pawls in engagement with the secondary ratchet wheels 35 and 36 so that as the free ends of the pawls 31 and 32 swing up and down the eccentric pivots 30 will be rotated to move the pawls 31 and 32 longitudinally back and forth.

A cord 41 has branches 42 and 43 connected to the free ends of the pawls 31 and 32 and the cord 41 extends through a housing 44 and is attached to a handle ring 45, said cord 41 being long enough to allow the pawls 31 and 32 to vibrate freely when it is desired to work the valve grinder. A knot 46 is formed in the cord 41 and an opening 47 is formed through the housing 44 large enough to allow the knot 46 to pass and a slot 48 extends downwardly from the opening 47 so that when the handle ring 45 is manually operated to pull the cord 41 the knot 46 will pass through the opening 47 and then when the handle ring 45 is released the cord 41 will pass downwardly into the slot 48 with the knot 46 on the outside of the housing 44, thereby holding the pawls 31 and 32 elevated out of engagement with the main pawl wheels formed by the annular rims 16 and 22 carrying the ratchet teeth 17 and 23 so as to render the valve grinder inoperative.

When the handle ring 45 is operated to pass the cord 41 through the opening 47 and released, the pawls 31 and 32 will press downwardly upon the main pawl wheels and then when the engine is operated and the cam shaft 8 rotated the stems 3 and 4 will be rotated step by step to rotate the valves 1 and 2, and the step by step motion will be varied by the eccentric motion of the pivots 30. The rotation of the valves 1 and 2 is caused by the up motion of the main pawl wheels and is due to the swing of the free ends of the pawls 31 and 32 in arcs relative to the pivots 30 and the advancement of a valve at each operation will be very slight and will be more or less according to the positions of the eccentric pivots 30.

If desired, independent cords may be attached to the pawls 31 and 32 instead of a branch cord so as to throw either pawl out of operation when desired without throwing the other one out, and it is obvious that wires or rods may be substituted for the cords.

Special attention is called to the fact that the valve upon the seat is slightly rotated by reciprocation of the other valve. This is due to the eccentric shaft. When the

pawl 32, for instance, goes up as in Fig. 1, 65 the eccentric shaft 30 is rotated to reciprocate the pawl 31 back and forth and when the eccentric is on the down stroke and moved forwardly the pawl 31 is pushed slightly to rotate the pawl wheel on the 70 valve stem 3, and of course when the pawl 31 goes up the pawl 32 is pushed outwardly to rotate the pawl wheel on the stem 4. This movement of the pawls upon their seats may be increased or decreased by increasing or decreasing the eccentricity of the shaft 29.

It is desirable that the rotation of the valves both on their seats and off their seats be very slight so that the grinding action 80 may be continued indefinitely without over-grinding.

Various changes may be made without departing from the spirit of my invention as claimed.

I claim:

1. In a valve grinder the combination with a valve having a reciprocating stem of a pawl wheel non-rotatably mounted upon the stem and having teeth extending in a 90 plane parallel with the stem; a bearing plate attached to the wall of the engine substantially on a level with the pawl wheels; a pawl pivotally connected to the bearing and engaging the pawl wheel so as to rotate the 95 pawl wheel step by step as the stem reciprocates; and means for moving the pawl longitudinally back and forth by the vibration of the pawl.

2. In a valve grinder the combination 100 with a valve having a reciprocating stem of a pawl wheel non-rotatably mounted upon the stem and having teeth in a plane concentric to and parallel with the stem; a bearing plate fixed to the water jacket wall; a bearing extending outwardly from the bearing plate; a shaft rotatably mounted in the bearing; an eccentric pivot upon the shaft; a pawl loosely mounted upon the pivot and engaging the pawl wheel upon the valve 110 stem; a secondary pawl wheel fixed upon the shaft; and a secondary pawl connected to the first pawl and engaging the secondary pawl wheel so that the valve will be rotated step by step as the stem reciprocates 115 and so that the eccentric pivot will be rotated as the main pawl vibrates.

3. In a valve grinder the combination with two valves having alternately reciprocating stems, of pawl wheels fixed upon the 120 stems; pawls mounted upon an eccentric shaft and engaging the pawl wheels; and means whereby the swinging movement of the pawls operates the eccentric so that the reciprocation of one valve stem will rotate 125 the other valve upon its seat.

4. In a valve grinder the combination with two valves having alternately recipro-

eating stems, of pawl wheels fixed upon the stems; an eccentric shaft; pawls loosely mounted upon the eccentric shaft and engaging the pawl wheels; secondary pawl 5 wheels fixed upon the eccentric shaft; and secondary pawls carried by the first pawls to engage the secondary pawl wheels so as to

rotate the eccentric shaft by the vibration of the pawls so that the reciprocation of one valve will rotate the other valve upon its 10 seat.

In testimony whereof I have signed my name to this specification.

HENRY M. CROWTHER.
